UNITED STATES PATENT OFFICE.

FRANCIS J. ADLER, OF WEST NEW BRIGHTON, NEW YORK.

KNOCKDOWN CONTAINER.

Application filed June 21, 1921. Serial No. 479,324.

The object or objects of my invention are to provide a new and improved form of collapsible container of the particular form commonly known as knock-down containers; in which type the various elements, when packed in knock-down condition, are in close compass and physically unconnected at what is their jointures when in the expanded state for use in shipments of products of almost innumerable kinds and characters, especially those in a dry condition; although the broad principle thereof, with provision for properly packing the joints, may be used for the carriage of liquids or even in some cases for transportation of gaseous fluids under pressure.

My said invention is not limited to any particular form of receptacle as regards interior or exterior contour; and while I have shown herein in the various views thereof from Figs. 1 to 7 the broad principle of my said invention or inventions herein first shown, described and claimed, in which Figures 1 to 7 a rectangular receptacle is shown, made up of a plurality of pieces, all of which when in the knock-down condition may be packed within certain of the individual parts forming certain of the boundaries of such receptacle when in expanded condition, so that in such knock-down condition it may be bound tightly into a package or packages, and occupy but comparatively little space in trans-shipment to the user; portions of the binding pieces used to bind and secure the parts in the expanded position, being used to bind them when in the knock-down bundle.

In Figs. 17 to 21, inclusive, I have shown the same broad principle of a knock-down receptacle shown in the foregoing figures of the rectangular box or crate form, as applied to a receptacle of the cylindrical central circumferential bellied or barrel form shown. And it is evident that the broad principle embodied in the two forms of rectangular and cylindrical container herein shown and described may, without departing from the scope of the broad claims hereof, be applied to receptacles of innumerable different forms, such as triangular, hexagonal, octagonal or dodecagonal, or any other suitable form.

To such ends broadly considered my said improved knockdown receptacles are each

made up of a suitable number of individual 55 interlocking separate wall and end or top and bottom pieces, which, when assembled in expanded position, will form a receptacle of the required shape and character, tightly closed and held in place by exterior binding-members in such manner that such receptacles cannot unintentionally have their pieces separated one from the other except by fracture and dismemberment 60 thereof. And being so constructed that all of such 65 members when disassembled, and placed in proper close juxtaposition one to the other, may be bound together in one bundle in the case of the boxes and in two in the case of the barrels, by the same binding member or 70 members or a portion thereof, as are used for the binding of the receptacle when in expanded form to be used as carriers of goods of any kind or character.

While I do not limit myself strictly to 75 the particular form or forms of construction of the several parts making up my improved form of knock-down carrier-receptacles herein shown and described, one broad principle runs through all the various forms 80 thereof to a greater or less degree, and that is that such receptacle comprises two integral top and bottom pieces usually and preferably, but not necessarily, of the single 85 piece form shown, and a plurality of interlocking end-pieces and side-pieces or panels, all of the end-pieces being preferably, but not necessarily, of one size, and all of the side pieces of another size; but both of interlocking-joint construction so as to permit 90 such panels to be interchangeably interlocked in any desired number to form receptacles of the shape or shapes to which they 95 are applicable, in any required plurality; so that the same unitary panel members may be used with different sized top and bottom members to form receptacles of many widely varying dimensional widths and lengths and consequently different capacities; and by having a series of like side and end pieces 100 of different lengths, boxes, etc., may be built up of an almost innumerable number of different capacities, varying in all three dimensions of space.

My said invention, or inventions, as fully 105 shown, described and claimed in the following specification, of which the accompanying drawings form a part, in which similar

letters or numerals of reference designate like or equivalent parts wherever found throughout the several views, and in which:—

- 5 Figure 1 shows a top plan view of one of the cubic rectangular type of receptacles, or knock-down collapsible boxes of my invention, when in the expanded goods carrying assembly.
- 10 Fig. 2 is a side view, in elevation, thereof looking in the direction of the arrow in Fig. 1;
- Fig. 3 is an end view thereof, in elevation, looking toward the right of Figs. 1 and 2;
- 15 Fig. 4 is a view thereof looking upward from the bottom in the direction of the arrow in Fig. 2; showing the arrangement of the exterior binding-strap members, positioned as they are in binding the receptacle 20 when in expanded working assembly and filled with the materials to be transported therein;
- Fig. 5 is a sectional end view of such receptacle, taken in central cross section on the line 5—5 of Fig. 2, looking toward the left; and Fig. 6 is a sectional view thereof taken in horizontal central section on the line 6—6 of Fig. 2, looking either from the top or bottom;
- 30 Fig. 7 is a view of all the parts comprising and making the entire expanded receptacle as shown in the foregoing figures, as knocked down and packed in small space to be shipped to the first user or returned to him for further use as a receptacle; such Fig. 7 being taken in vertical longitudinal section substantially showing the top cover inverted on the bottom and the side panels and extension binding members, 35 Fig. 13, enclosed therein.
- 40 Fig. 8 is a view in detail of one of the securing joints whereby the side or end plates are interlocked, showing in dotted lines the right hand plate slipped back out of engagement with the coacting hook upon the left hand plate and in position to be wholly disengaged by being forced outward away from what is the bottom of Fig. 8.
- 45 Figs. 9 to 13 inclusive are details on an enlarged scale from that of Figs. 1 to 7, showing the securing or binding-straps, etc., used to secure the rectangular type of my improved form of receptacle, in either the expanded working arrangement, shown in Figs. 1 to 6, or in the knocked down return shipping arrangement shown in Fig. 7.
- 50 Fig. 14 is a top plan view, in diagram, of such rectangular box showing one form of the arrangement into elongated rectangular form of box, in which one type of corner pieces and connections are used, and showing how the panel pieces of different lengths at the sides and ends can be used interchangeably either as sides or ends, to make,

with properly constructed and proper chamfered top and bottom pieces, a wide variety of boxes of different dimensions.

Fig. 15 is a like diagrammatic view of a modified form of construction, in which, instead of having two pieces forming the corner members and interlocking at the corners, a single piece with a strengthening coil at the center is provided to act as a corner piece in certain cases and for certain kinds of receptacle, which is universal in its application and may be used interchangeably with the panels and the top and bottom pieces shown in the foregoing figures;

Fig. 16 is a view in detail looking from the top of a modified form of panel joint for connecting together at the interlocking intersecting edges the various panel pieces, wherein the joint while being of the same type and character, broadly, as shown in the preceding figures, is made stronger as to exterior or interior strains of the metal in handling the containers roughly in the course of shipment, by reason of having at the joint on each interlocking member a strengthening groove which also acts as a shock absorber and which may or may not extend the entire length of such member.

Fig. 17 is a side view, in perspective elevation, of a cylindrical bellied substantially barrel-form type of container, embodying the same general broad principles of construction and assemblage as in the preceding figures of the rectangular type.

Fig. 18 is a view of such cylindrical container shown in Fig. 17, taken in central horizontal section on the line 18—18 of Fig. 17, looking from the top.

Fig. 19 is a view of the same device taken in central vertical section on substantially the line 19—19 of Fig. 18, looking in the direction of the arrow.

Fig. 20 is a top plan view of the same structure, looking downward in or on Fig. 17, showing the particular arrangement of the securing straps or members, by which the top and bottom and side members are secured together in the expanded and goods-carrying position shown in Figs. 17 to 20, inclusive.

Fig. 21 is a view in central vertical section of the top and bottom pieces of such cylindrical barrel-like form of receptacle, showing the manner in which they are assembled together and secured in a small package in the knock-down, non-expanded return package condition when returned to the owner for being used for further shipment.

Fig. 22 is a like view in central longitudinal vertical section of the vertical stave pieces or panels, in this case eight in number, making up the cylindrical portion of said container.

Fig. 23 is a longitudinal elevation of the

cylindrical barrel stave in assembly or bundle form, for shipment or storage.

Fig. 24 is a view in plan and elevation of the stave reshipping caps shown as applied to the knock-down cylindrical form where the staves are too long for enclosure within the heads or ends, and showing the means for attaching binding straps.

Fig. 25 is a similar view in plan and elevation of the panel reshipping caps for containers where the panels thereof are too long for enclosure within the top and bottom members, and showing the strap attaching means.

Fig. 26 is a fragmentary top or bottom plan view showing a modified form of pressure-resisting or reinforcing construction for jointures of the panels and tops and bottoms of the rectangular forms, and for the staves and heads or ends of the cylindrical form of containers.

Fig. 27 is a sectional view on the line 27—27 of Fig. 26, showing the reinforcing angle member with the bead on one side thereof, positioned in support of the head or top or bottom members and the stave or panel members.

Fig. 28 is a plan view of a container having end and side members of different sizes;

Fig. 29 is a side elevation;

Fig. 30 is a front elevation;

Fig. 31 is a plan sectional view on the line 31—31 of Fig. 29.

Referring to the drawings:

While I have shown herein only a rectangular and cylindrical form of the container, I do not intend in the broad claims hereof to in any manner limit myself strictly to such forms, as I consider that the broad principle of my said invention or inventions as hereinafter set forth in the broader claims of this application, cover and include receptacles of any other type than the rectangular, cubic or cylindrical forms; such for instance even as triangulair, hexagonal, octagonal, polygonal, and any other forms of receptacle to which the broad principle hereinafter pointed out in the claims may be applied.

In practice my receptacle of whatever form, may be formed of various materials, according to the particular character of the goods to be put therein for shipment; for certain purposes the best material is sheet metal, stamped, pressed, or spun, or otherwise formed into the proper contoured shapes and sizes; in other cases it may be of cast metal and usually and preferably in the case of the barrels the ends are so made of cast metal, but it is evident that for certain purposes and uses the parts may be wholly or partially of wood, pressed fiber, cellular-paper board; or such substances of any suitable form of non-metallic material may be provided with intersecting portions or slip-

joints of metal secured to the edges or ends thereof in any desired and suitable manner with equal effect, without departing in any manner from the broad scope of the invention herein first disclosed and claimed.

The broad principle of my invention, which runs through all the various modifications of the same is clearly shown and most easily described with reference to the cubic or rectangular form of container shown in Figures 1 to 16 inclusive. As shown therein such rectangular receptacle comprises in its simplest form (Figs. 1 to 8 inclusive) a top piece 11 and a like bottom piece 12 adapted to receive at either end two comparatively narrow panel members 13, and at the sides two somewhat broader panel-members 14; which may be of any desired form of construction but may be made of sheet steel, aluminum, brass or other metallic material; are usually and preferably stamped, pressed or otherwise formed with inwardly or outwardly extending ribs 15, which are stamped or otherwise formed therein to add greater strength and rigidity without diminution of the packing space within. In the rectangular or cubic form being now first described, I have found the barred and cross-barred forms shown in Figs. 1 to 5 to be good and efficient strengthening members.

As clearly shown in the drawings, especially in Figs. 5 and 6, the top and bottom pieces 11 and 12 each comprises an interior bottom plate which may be integral or made up of a plurality of parts of sheet metal pressed or stamped into proper form and thereafter assembled and secured together into one homogeneous top or bottom piece by spot welding or in any other desired manner. Each of said top and bottom members also comprises, preferably but not necessarily, upwardly extending angle or end flanges 16, and like side flanges 17, within which is located a secondary inner flange 17' or 16' as the case may be, according to whether it is an end or a side member. As clearly shown in Figs. 5 and 6 these inner flanges extend inward a sufficient distance where the panels join so that a rectangular securing chamfer or socket is formed to receive and hold the interlocked panels firmly in position against lateral movement, when the top and bottom are in place, that is, expand or spread out the wall members into interlocked position, so as to prevent disengagement of the jointures or interlocking portions, members or hooks of the side or end panel members, as the case may be. And this broad principle extends also to the circular or any other of the various modified forms of construction of container embodying such broad principles.

The end and side panels 13 and 14 are each provided with interlocking joints, by which

they may be all interchangeably assembled in any desired plural number to be used with top and bottom pieces of any required size to form the size of receptacle desired for use at the moment. And, while I do not limit myself to any particular type of separable joint or jointure, I have found in practice that the type of joint shown in Fig. 6 is a good and efficient one for such use, 10 easily assembled and easily taken apart and held, when in position in the top and bottom pieces of required form, and when securely bound by the binding members, to be a rigid joint so that no amount of handling 15 or concussion, not sufficient to fracture the panels or the bottom or top members, will ever serve to cause the disengagement of such joint so as to disintegrate the receptacle and cause spilling of its contents. As 20 shown in such Figures 1 to 8 inclusive, and especially on an enlarged scale in detail in Fig. 8, one of the central joints joining two of such side or end panel-members or pieces are shown in full lines in the interlocked position, and in dotted lines in the releasing 25 position. And each of such panel members comprises a central panel or sheet section 18, having at either end an integrally formed hooked securing member 19, interlocking 30 with a like hooked securing member 19', formed in like manner by pressing, bending, rolling or drawing, in the adjacent edge of its coacting interlocking panel-member.

These hooks or jointure members are usually of the slip-form, shown in detail in Fig. 8, or the slightly modified form shown in Fig. 16, and in either form they are so made in the course of formation of the panel as to either slide easily backward into the position 40 shown in dotted lines in said Figs. 8 and 16, or to slide longitudinally; but in some cases they may be made so narrow as to only slide longitudinally, and in such case the two hooks are of substantially the same length 45 so that the shoulder 18' abuts against the end 20, so as to lock the joint against any except sliding movement in the direction of the axes of the two interlocked hooks. It is evident that a variety of corner pieces and 50 means of interlocking may be used in place of those shown in Fig. 6. In such Fig. 6 there are only two panels on each end and two on each side, and to form the joint one set of such corner abutting panels is provided with the interlocking hooks 18, with the hooks in parallel plane with the panel itself, as indicated in Fig. 14 at 18, while the coacting panel piece to form the corner has at one end the parallel hook 18, and at the 55 other the right angle hook 22, all of which is clearly shown at the corners in Figs. 6 and 14.

The required number of panels having been interlocked and fitted into the bottom piece, the top which is merely an exact rep-

lica of the bottom piece, is fitted upon the top of the panel-members after the receptacle has been filled, and is pressed down into position and the longitudinal securing strap 25 and the cross-like securing strap 26 are placed in position. Such securing straps are shown in detail in Figs. 9 to 13, and the adjustable securing hook member 27 is of substantially the shape shown, formed integrally with or secured to the thin metal strap extension 27' having at the end the usual downwardly and thin upwardly extending securing hook member 28, the hook 28' of which, when in position, has passed over it the eye end 29 of one of the intermediate strap-members 30, shown in detail in Fig. 13, while the hook 31 of such intermediate securing-strap member 30 is passed through the eye 32 of the bottom strap member 33, shown in detail in Fig. 11, which is contoured as shown to have the end depressions 34 into which fit the downward extending portions of the bottom members, all as clearly indicated in Figs. 1 to 6 inclusive. Secured to the right hand extension of the securing-straps (Figs. 3, 9 and 10) and co-acting with the securing hook 27, is the screw yoke-member 35 having a screw threaded orifice 36, which carries the adjustable screw tightening-bolt 37 bearing upon the left hand concaved face of the hook 27, as shown; and looped over the opposite end of the yoke 35 by a loop 38, and spot welded or riveted so as to be firmly secured to said yoke, is the right hand extension of the top longitudinal or cross securing strap, as may be the case, which is provided with a securing hook 28 and 28' of the same shape and contour as the one attached to the adjusting hook 27.

And by this arrangement it will be seen that when the pieces are all assembled together, as shown in Figs. 1 to 6 inclusive, by merely tightening up on the screws 37, working in the yokes 35, sufficiently, that the binding straps will be rigidly strained to straighten out the curves in the end or side intermediate straps 30, and the top, bottom and sides of the receptacle thus thoroughly locked against accidental dismemberment or collapse.

It will be noticed, in Figs. 1, 2, 3, 4 and 6, that the securing straps or devices referred to are not arranged at right angles to one another, and the purpose of this is to add to the security by locating the members 30, in each case, in the central lock-joints of the central joint so as to completely fill the open portion of the slip joint indicated by the dotted hook in Fig. 8; and by its presence therein add additional security to the work of the top and bottom pieces in preventing accidental slipping of such interlocking joints.

The disassembly, of course, is carried

about in the same manner. When it is desired in the first instance, upon purchase from the manufacturer, or upon returning the receptacle to the owner for further shipments, to save freights, handling, etc. my improved receptacle is disconnected into more or less complete disassembly. After the bottom has been filled with the end and side pieces 13 and 14 and the side straps 30, the top cover member is inverted thereon and the two top and bottom binding members 25 and 33 are adjusted into position thereon, as clearly indicated in Fig. 7. The hooks 28 of the two adjustable yoke or binding members are then passed through the loops 32 of the bottom straps 33 and by manipulation of the screws 37 of yoke member 35, the said top and bottom members, with the end and side pieces and side straps enclosed therebetween, are securely bound into a relatively small compact bundle or package, for return shipment or storage.

So far as described it will be seen that the corner pieces are in two sections, but in the detail Figure 15 I have shown a modified form of corner-piece which, for certain uses, is preferable to the one shown in two pieces, and this comprises two securing hooks 18, the hooks of which are at substantially right angles to each other and joined together by a substantially cylindrical or segmental integral center-member 39.

In Figs. 17 to 20 inclusive, I have shown a cylindrical form of barrel-like container which, for certain goods, it is preferable to use instead of the cubic or rectangular or other like plane faced straight panel forms heretofore described. As shown in the drawings, especially in Figs. 18 and 22, in one of the many forms in which such barrel container may be made, the same comprises heads H and H', usually but not necessarily of stamped or cast metal formed into suitable form in any preferred way, although in some cases for certain purposes such heads may be made of fiber, turned out of wood, press-board, or a combination of metals with such materials; or of any suitable material that may be used. The main design of the heads H and H', in so far as regards its having an annular bounding peripheral socket 50 into which are fitted, when in position, the ends of the staves 51, and which annular groove 50 performs precisely the same function, is the same as the securing slot shown and described in connection with the rectangular form of container. The barrel staves 51, as shown in the drawing, especially in Fig. 18, are usually and preferably, but not necessarily, eight in number; as I have found that this is a most convenient number for a great many reasons. Each stave 51 is provided along one longitudinal edge with an outward, and at the other like edge with an inward, securing-hook, sub-

stantially almost precisely similar to the securing hooks 18 of the rectangular boxes hereinbefore described; whereby such staves are secured together in identically the same manner save that they are arranged in a circle instead of a rectangle as are the panels and corner-pieces of the first type. They are then placed in position in the heads H and H', as clearly shown in Fig. 19, the shape of the slot 50 being such as to prevent side slip movement to loosen and disconnect the hook-joints, such slot being provided for that purpose with enlargements into which the hook-joints fit securely when once the staves are in position in the heads H and H'. The grooves 78 in the heads H and H' adjacent to the flanges 79 permit the formation of elongated grooves 50 to afford an extended securing anchor for the ends of the staves 51 without requiring the chimes 80 of the barrel unduly to protrude.

While the staves may be made of many, almost innumerable, different shapes, lengths and sizes, and especially when made of metal, they are usually and preferably provided with a plurality of longitudinal stiffening-ribs pressed, rolled or formed therein in any way, as indicated at 54 of Figs. 18 and 20, and such strengthening ribs usually are forced outward, as shown, and are usually and preferably two for each stave or peripheral side-piece of such container or barrel. The securing-straps of the barrel type of container are substantially identical in every respect, except as to size, with those described for the rectangular box type of receptacle, as hereinbefore set forth, and therefore no further description is thought to be needed. But on account of the peculiar construction and shape of the various parts of the cylindrical type of container, it has been found best to make two packages of such containers when in the return and knock-down position for shipment, and for this purpose it is necessary to add new elements which are two stave securing socket members 60 struck up or pressed from sheet metal, and preferably are provided with spring-tongues at either end, indicated at 61, Figs. 24 and 25, which, by their tension, hold such stave-securing end members in position in the central depressions 52 of the heads H and H' while in transit; and these can be easily pried out when the barrel is disassembled and the four longitudinal securing-members 30 disconnected from the bottom and top securing members 28 and 33 and secured by their looped and hooked ends, as the case may be, in the appropriate orifices of the stave securing end members 60 into a compact bundle, as shown in Fig. 22, while the two securing members 33 and the adjustable yoke members 35 are secured together around the two heads, all as clearly indicated in Fig. 21 in detail, when the entire device

will be in knock-down condition for return shipment.

In Fig. 26 and Fig. 27 I show a section and fragmentary plan of a modified form of head or end reinforcement construction that may be incorporated in all types of containers. In this modification, which is desirable from the standpoint of manufacture, there is shown an angle member 70 having a bead or rib 71 pressed or rolled in one leg or flange thereof to engage with a corresponding bead or rib 73 pressed or rolled in a head such as the heads H and H', Fig. 19, or in a cover such as the top and bottom ends or covers 11 and 12, Fig. 2; which angle is secured to the heads or covers either by riveting or spot-welding, as at 76, Fig. 26. The other leg or flange of the said angle member 70 abuts and conforms 20 to the inside of the stave or panel members, which the exception of the extreme end thereof which is slightly curved inwardly and which forms the stave or panel directing portion of the retaining slots 50 (Fig. 21) 25 and 16' (Fig. 6).

The slot forming stave or panel overlapping portion 74 of the top 11, bottom 12, or head members H and H', may be reinforced by a wire rolled into its lower edge, as shown 30 in Fig. 27, and which reinforced edge permits of removal of the head or top or bottom members by blows struck upon such edge, without injury thereto.

As shown in detail in Fig. 23, (inasmuch 35 as the adjustable yoke members shown in Figs. 9 and 10 are not used in the stave packing but only in the head packing, as shown in Fig. 21), in order that the package of staves shown in Fig. 22 can be secured 40 together by longitudinal strap members 30, the stave-securing socket members 60 are provided with the slots 61. The said strap members 30, which are used only for binding purposes where the stave or panel is too 45 long for enclosure within the ends or heads, are each provided at one end with a hook portion 31 and at the other end thereof with a loop portion 29. When the container is assembled in knock-down state it is securely 50 bound for return shipment or storage by engaging the hook portion 31 of strap member 30 with the slot 61 in the cap 60. In order that a constant retaining pressure may be exerted I place between the looped portion 29 and the slot 61 of the other cap 60 on the opposite end of the assembled knock-down package, a spring 63. The foregoing description covers the connection of but one 55 of such retaining strap members, which strap members number four in number in the pres-

ent instance, but which number may be increased or diminished as desired.

Figs. 28, 29, 30 and 31, are views of a container having end, or top and bottom, members 100 and 101, respectively, of different area; and panel or wall members, 105, of different lengths and widths.

Having thus described my invention I claim:

1. A receptacle comprising wall members, 70 hooked formations on the edges lateral of said wall members, the hooked formations of adjacent wall members hooking into one another, and means for receiving the end edges of said wall members to expand the hooked 75 formations of said wall members into interlocking position.

2. A receptacle comprising wall members, 80 hooked formations on the edges of said wall members, the hooked formations of adjacent wall members hooking into one another, and top and bottom members for expanding the hooked formations of said wall members into interlocking position.

3. A receptacle comprising wall members, 85 hooked formations on the edges of said wall members, the hooked formations of adjacent wall members hooking into one another, and top and bottom members, there being channels along the edges of said members to receive the end edges of said wall members to 90 expand the hooked formations of said wall members into interlocked position.

4. A receptacle comprising an end member 95 of one area and a second end member of a different area, and interlockable side wall members of different widths interchangeably connected to said end members.

5. A receptacle comprising end members and interlockable wall members; said end 100 members being adapted to expand said wall members.

6. A device of the class described having a panel piece provided with an interlocking edge portion, said edge portion being bent 105 to form a hook portion, and a second panel piece provided with an interlocking edge portion to cooperate with said hook portion, said second edge portion being offset and bent to form a second hook portion, the offset of said second edge portion being spaced 110 from the free edge of the hook portion of said second edge portion to form a clearance of at least the length of the first mentioned hook portion in order to permit receiving 115 the first mentioned hook portion directly without first sliding it the full length of the second mentioned hook portion.

FRANCIS J. ADLER.
